UNITED STATES PATENT OFFICE.

JAMES F. CRAVEN, OF PITTSBURGH, PENNSYLVANIA.

PAPER BARREL OR KEG.

1,234,633.

Specification of Letters Patent. Patented July 24, 1917.

Application filed November 16, 1912. Serial No. 731,855.

To all whom it may concern:

Be it known that I, JAMES F. CRAVEN, a resident of Pittsburgh, in the county of Allegheny and State of Pennsylvania, have invented a new and useful Improvement in Paper Barrels or Kegs, of which the following is a specification.

This invention relates to paper barrels, kegs, or other receptacles. The object of 10 the invention is to provide an improved article of the character described, which is inexpensive to manufacture, is light and quite strong for its weight, and can be handled in the same manner as ordinary receptacles now in use.

The invention comprises the construction and arrangement of parts hereinafter described and claimed.

In the drawings Figure 1 represents a 20 view, partially in side elevation and partially in section, of a barrel or keg constructed according to my invention; Figs. 2, 3, 4 and 5 are enlarged detail sectional views of the same and showing the successive steps in the formation of the end joint; Fig. 6 is a view corresponding to Fig. 1, and illustrating modifications; Fig. 7 is an enlarged detail sectional view of the same; Fig. 8 is a detail view, showing a modification; Fig. 9 is a broken out perspective view illustrating a modified form of the invention; Figs. 10 and 11 are similar views showing other modifications; and Fig. 12 is a detail perspective view, partly broken out, 35 of another form of the invention.

The barrel or keg shown in the drawings comprises a paper cylinder or tube 1 of any desired length, diameter and wall thickness. This is preferably formed by rolling or 40 winding a sheet or strip of paper or paper-board into a tube of one or more superimposed plies, securing said plies together during the rolling or winding by a suitable adhesive, and then cutting the tube thus formed into one or more sections of the proper length for the desired barrel or keg. The ends of the tube are closed by paper 45 caps or heads 2, which may be merely flat disks of paper or pasteboard, as shown in Fig. 6, but preferably are cupped or shaped to form a rim or flange 3 which closely fits the inner wall of the tube 1. The caps or heads may also be bilged or arched, as shown in Fig. 6, to make them stronger. 50 The peripheral portions of the caps or heads 2 are seated against shoulders 4 in the tube.

which shoulders may be formed by pasting or otherwise securing rings or hoops of paper, paper-board or other material to the inner wall of the body 1, but preferably are 60 formed, as shown, by the end edges of an inner tube or cylinder 5, which may be formed of paper in the same manner as the body 1, and is shorter than said body. The inner tube or member 5 may be formed of 65 one or more plies and may or may not be pasted or glued to the inside of the outer member 1, as preferred, but in any case fits tightly within and materially strengthens and reinforces the same. Preferably, 70 the inner tube 5 will be the substantial body and will be made of greater thickness and weight than the outer tube 1, and of cheaper material. The outer tube will be of thin, tough, strong stock, while the inner tube 75 will depend more for its strength on the weight and thickness of the material.

Either or both of the end caps or heads 2 may be provided with a ring or bushing 6, which may be formed, for example, of 80 sheet metal with one end portion crimped or beaded around the edges of an opening 7 in the head or cap, thus forming a filling or discharge orifice, and, if desired, caps or closures 8 may be threaded upon or otherwise secured to the bushing 6. This, however, is not essential and may be omitted, in which case the end heads or caps will be imperforate.

The chimes or end portions 9 of the barrel or keg project beyond the end shoulders 4 of the inner tube 5. Moreover, when the caps or heads 2 are cupped or flanged, as illustrated in Fig. 1, the chimes 9 project beyond the edge of the flange 3. This projecting end portion 9 of the tube 1 is utilized to firmly secure the heads or caps to the receptacle and provide a strong and tight joint at the ends thereof. For this purpose the end portion or chime 9 of the tube 1 is 90 bent or folded inwardly upon itself, so that its end edge 10 forms a shoulder or stop covering the peripheral edge portion of the cap 2, thus locking the same in place. In the case of the receptacle shown in Figs. 1 and 12 the end portion 9 of tube 1 is 95 bent around the rim or flange 3 of the cap, thus forming an interlocked joint, and not only firmly securing the end cap in place and preventing it from being pulled out of 100 the joint in either direction, but also giving 110 a very tight joint which will prevent leak-

age of the contents. When the receptacle is filled the outward end thrust upon the heads or caps is transmitted to the flanges 3 and is taken up entirely by the channel 5 or U-shaped chime 9 of the barrel.

To further strengthen the joint between the body and end heads or caps and prevent rupture or breakage, I provide a retaining member or keeper 11, as shown in Figs. 7 10 and 12, which is in the form of a hoop or ring and may be made of paper, wood, metal or the like, but preferably comprises a short section of paper tube. This hoop or ring is formed to snugly fit within the 15 interior of the chime 9 of the barrel, and not only acts as a keeper to prevent the bent or folded portion of the outer tube 1 from opening up and thereby releasing the flange 3 of the cap, under conditions of use, but 20 also gives a neat finish to the end of the barrel or keg, in that it hides the creases or folds which unavoidably are formed in bending the ends of the outer tube inwardly.

In constructing or assembling the barrel 25 or keg, paper tubes of the proper size are formed or selected for the outer tube 1 and inner tube 5. The inner tube is slipped into place within the outer tube, and pasted or glued thereto if desired. End caps or heads 30 2 of the proper size are then placed in position with their peripheral portions resting on the shoulders 4 at the ends of the inner tube 5. These caps may be disks, as shown in Fig. 6, but preferably are cupped or flanged, as described and as shown in Figs. 35 1 and 12. The projecting end portions or chimes of the outer tube are then softened by moistening the same or by steaming, and are then subjected to the action of a series 40 of forming or breaking rollers, to bend the end portion of the outer tube inwardly, either upon itself, as shown in Fig. 6, or to inclose the rim or flange 3 of the cap, as illustrated in Fig. 1. This bending action 45 will be performed upon a suitable machine embodying a set of rollers brought successively into action to gradually bend the end of the tube 1 inwardly by successive steps, which steps are indicated in order in Figs. 50 2, 3, 4 and 5. Machines of this general type are well known and require no further description. To enable the tube 1 to be easily bent or folded at its end, as described, it may be grooved or creased circumferentially 55 on its outer surface, as indicated at 12. When this is done the outer fibers stretch more readily during the bending operations and there is less liability of rupture. After 60 the end of the tube 1 is bent inwardly, the retaining hoop or ring 11 is pushed into place endwise, and then secured by gluing, pasting, or otherwise, if desired. The circular shape of the hoop or ring adapts it well to resist the inward bending or opening 65 of the bent end portion 9 of the tube 1, which

must necessarily occur if the joint ruptures. The retaining hoop or ring thus locks the end cap in place and prevents the weight of the contents of the receptacle from tearing the peripheral portion thereof from the 70 joint. Either before or after the application of the retaining ring or hoop to the receptacle, the end of the receptacle may be treated with a non-absorbent substance, such as bakelite or paraffin, to make a liquid and 75 gas tight joint, although this is not essential when the receptacle is intended for containing certain classes of materials.

The barrel or keg described is intended particularly to be made in smaller sizes to 80 contain solid substances like nails, nuts, bolts, sugar, flour, and the like, although it may be made as large as desired and may contain other substances. When the substance to be transported is unusually heavy, 85 as nails, it may be preferable to provide the paper walls of the receptacle with suitable reinforcement 15. This may be done by laying between the successive plies of the paper forming the tubular body a wire, or textile 90 fabric, such as wire screen, cloth or canvas, which may be wound between the plies of the paper tube, as shown in Fig. 12, during its manufacture. The wires, fibers or threads of this fabric will preferably cross 95 each other at right angles and be placed in the paper tube, as shown in Fig. 12, so that in the finished barrel or keg they will run both longitudinally and circumferentially thereof, thus forming not only longitudinal reinforcing bands but also a series 100 of practically continuous circular ties or bands extending completely around the receptacle, which effectively prevent the body from bulging or rupturing outwardly. In 105 addition, the reinforcement, extending as it does, clear to the ends of the paper tube, and through the bent or folded chimes 9, will largely prevent cracking and rupturing thereof during the folding of the tube to 110 form the end joints. This is especially true if the reinforcement is of textile fabric, such as cloth or canvas, which becomes so embedded in the adhesive between plies that 115 it is practically an integral portion of the paper tube itself, thus preventing splitting of the tube and separation of the plies thereof on folding. The metal or fabric reinforcement may also be applied to either the inner or outer surface of the tube, or both, if 120 desired.

The paper tube or tubes forming the body may also be reinforced with paper, either laid between the plies of the tube or applied to its interior or exterior surfaces, or both. 125 In this case the main bulk of the tube will be of some cheap stock and the reinforcement of thin, strong, tough paper, such as is known in the trade as Craft stock.

The paper end caps or heads 2 may also be 130

reinforced in any of the ways described for reinforcing the tubular body.

It will of course be understood that the barrel or keg may be formed of true cylindrical shape, as illustrated in Fig. 1, or may be bilged, as in Fig. 3, so that it may be easily placed on end and otherwise handled in the ordinary manner. In the latter case the tubular barrel body will be softened by 10 steaming or the like, immediately after its formation and before the adhesive has set, and then expanded within forming dies of the proper shape to give the barrel the bilged form. In this connection it will of course 15 be understood that the term "tube" as used herein, means a bilged member as well as a true cylinder.

The barrel or keg described may be made very light and is constructed entirely of 20 paper. It is consequently inexpensive and for most purposes will compete in the market with ordinary barrels made of wood or metal. Obviously, when made in quantities by one manufacturer for use by another, the 25 barrel will first be constructed with one head or cap secured in place and delivered in this shape to the user, who, after filling the barrel or keg with the contents, will then apply the second head or cap to close the same.

30 Under some circumstances it may be inconvenient for the user of the barrel or keg to employ a special machine or apparatus for securing the second head or cap in the barrel or keg. To provide a keg in which the ends 35 may be readily closed or secured by hand, I may use the construction illustrated in Figs. 8 and 12. In this form of the invention the projecting end portions or chimes 9 of the barrel or keg are suitably slotted or kerfed 40 at intervals, as at 20, to form a series of flaps or leaves 21. The slots or kerfs 20 will preferably be of V-shape, as shown, to secure a more perfect fit, and extend inwardly from the end edge of the outer tube not quite to 45 the end edge of the flange or rim 3 of the end head or cap 2. With this construction, one end head or cap is first secured permanently in the keg or barrel. This may be done at the factory, as hereinbefore described,

50 or by the user of the barrel or keg, in the same manner as the second head or cap about to be described. The keg or barrel is then filled with the contents and the end head or cap 2 slipped into place with rim 3 resting 55 on the shoulder 4 of the inner tube 5. The flaps or leaves 21 between the spaced kerfs or notches 20 are then folded or bent inwardly by hand around the flange or rim 3 of the end head or cap 2, from the position 60 shown in Fig. 8 to that shown in Fig. 12. They may be secured in place by a suitable adhesive, or if desired a keeper or retaining member 11 may be slipped in place within the folded chime, as before described. So 65 far as its other details of construction are

concerned, the keg or barrel described, and illustrated in Fig. 8, may be of any of the forms heretofore described and illustrated in the drawings.

I may also in some cases dispense with 70 folding or bending inwardly the end portion of the body of the outer tube 1. Such construction is illustrated in Fig. 9, where instead of having the end of the outer tube 1 project beyond the edge of the rim 3 it extends only to the edge of the rim or flange. The end cap or head is then secured in place by folding over the projecting end portions 75 22 of the reinforcement 15, which may be of any of the forms heretofore described. In 80 the particular construction illustrated in Fig. 9 the reinforcement comprises strips or bands of metal placed between the inner and outer tubes 5 and 1, or between the plies of the outer tube, said strips or bands being a 85 little longer than the outer tube, so that the end portions 22 thereof form clips or flaps which can be bent inwardly in the manner described and shown. The strips or bands 22 may be formed of comparatively thin 90 metal, from considerations of economy and pliability, in which case it may be necessary to insert a retaining member or keeper 11 and secure the same within the flange or rim of the end cap to prevent the folded flaps 22 95 from being bent outwardly.

The same effect may also be secured in case it is desired to utilize an end cap or head 2 formed of a simple disk, as illustrated in Fig. 10. In this case the outer edge of said head or cap rests against the end shoulder 4 of the body of the tube and a separate ring or flange 23 of paper or other suitable material is placed within the projecting end portion 9 of the tubular body. Said ring is 100 of such width that its outer edge is opposite the end edge of the chime 9 and it covers the rim of the cap 2 and holds the same down to its seat on the shoulder 4. It practically forms a separate rim or flange for the end 105 cap and secures a better fit of the same within the outer tube. It is also cheaper to manufacture than the cupped head or cap.

Other types of reinforcement than the simple bands or strips 22 just described may 110 be employed. For example, the reinforcement may comprise paper or a wire or textile fabric, such as hereinbefore referred to. This fabric may be placed within or between the plies of the outer tube, or between the 115 outer and inner tubes, or may be applied to the outer surface of the outer tube. Since the fabric is comparatively pliable and may be more easily folded than the paper body or even the metal strips 22 referred to, 120 the projecting end portion of the reinforcement may be continuous all the way around the circumference of the keg or barrel. Such fabric is illustrated at 24 in Fig. 11, and is 125 shown as applied to the outer surface of the 130

outer tube, the end of the fabric reinforcement being bent or folded inwardly around the ring or flange of the end cap or head and secured in place by a suitable adhesive.

5 As in the other cases described, additional strength may be given to the structure by the employment of a retaining member or keeper.

What I claim is:—

- 10 1. A barrel or other receptacle, comprising a paper body formed to provide shoulders inwardly of the ends thereof, end caps or heads having their peripheral portions seated on said shoulders, the projecting end portions of said body being notched or kerfed at intervals to provide a series of flaps adapted to be folded inwardly over the peripheral portions of the end caps or heads, and reinforcing or stiffening means for said
- 15 flaps comprising strands embedded in the paper body and extending through said end
- 20

flaps and connecting flaps at opposite ends of the receptacle.

2. A barrel or other receptacle comprising a tubular body formed to provide inner 25 shoulders inwardly of the ends thereof, end caps or heads having their peripheral portions seated on said shoulders and provided with flanges fitting within said tubular body, the projecting end portions of said tubular 30 body being notched or kerfed at intervals to form flaps adapted to be bent inwardly around said flanges to lock the end caps or heads in place, and a retaining loop or ring located within said folded flaps and arranged to hold the same in place.

In testimony whereof, I have hereunto set my hand.

JAMES F. CRAVEN.
